LAMP SHADE

Heinz K. Weber, 3132 Los Olivos Lane,
La Crescenta, Calif.

Filed Mar. 8, 1962, Ser. No. 69,146

Term of patent 7 years

(Cl. D48—16)

FIG. 1 is a side elevational view of a lampshade showing my new design,

FIG. 2 is a top plan view of FIG. 1,

FIG. 3 is a bottom plan view, and

FIG. 4 is an enlarged fragmentary sectional view taken substantially along line 4—4 of FIG. 1.

I claim:

The ornamental design for a lampshade, substantially as shown.
